MANUFACTURE OF FOOTWEAR

Henry B. Gorman, Lynchburg, Va., assignor to
Compo Shoe Machinery Corporation, New
York, N. Y., a corporation of Delaware

Application August 31, 1935, Serial No. 38,686

2 Claims. (Cl. 12—142)

This invention relates to the manufacture of footwear and more particularly to the making of welted shoes.

A general object of the invention is to provide 5 a welted shoe of improved construction which may be made rapidly and economically.

More particularly, objects of the invention are to provide methods of making welted shoes in which a welted upper may be quickly and efficiently lasted by means of cement to provide a lasted 10 upper construction which is well suited to have an outsole affixed thereto, also preferably by means of cement.

Other objects of the invention will in part be 15 obvious and will in part appear hereinafter.

The invention accordingly comprises the several steps and the relation of one or more of such steps with respect to each of the others, and the 20 article possessing the features, properties, and the relation of elements, which are exemplified in the following detailed disclosure, and the scope of the invention will be indicated in the claims.

For a fuller understanding of the nature and 25 objects of the invention reference should be had to the following detailed description taken in connection with the accompanying drawing, in which:

Fig. 1 is a bottom plan view of a completed shoe 30 constructed in accordance with the principles of this invention, parts thereof being broken away better to show the construction;

Fig. 2 is a fragmentary sectional view through the edge of an assembled upper used in the construction of Fig. 1;

Fig. 3 is a fragmentary transverse sectional view through the inseam portion of a shoe;

Fig. 4 is a fragmentary transverse vertical sectional view corresponding to Fig. 3, but showing an outsole attached;

Fig. 5 is a plan view of a fastening piece used in another form of shoe embodying principles of this invention;

Fig. 6 is a fragmentary sectional view of the edge of an assembled upper, utilizing the fastening piece of Fig. 5;

Fig. 7 is a fragmentary transverse vertical sectional view across the inseam portion of a shoe; and,

Fig. 8 is a fragmentary transverse vertical sectional view similar to Fig. 7 but showing an outsole attached.

Referring more particularly to the drawing, and first to Fig. 2, there is shown a portion of an assembled upper 10 which may be of any conventional plied arrangement of upper and lining ma-

terials. This upper 10 is trimmed so as to approach but preferably not overlap an insole when pulled over a last on which such insole is located. That is, it has a very slight lasting allowance. Prior to lasting operations, such upper has a welt 11, preferably of leather, superposed along its outside face, and a fabric fastening strip 12 is superposed along the outside face of such welt. This strip may be of heavy canvas, duck or other suitable strong flexible material. These superposed parts are sewed together by a line of stitching 13, located closely adjacent the edge of the upper.

An insole 14 is then located on the bottom of a last 15, and the upper with its attached welt and fastening strip is pulled over the last. In this pulling over operation, the fastening strip 12 is doubled back on itself so as to overlap the insole, and this overlapped portion is cemented thereto, preferably by means of pyroxylin cement. The 20 fabric 12 affords a good base for cement and is adapted to provide a firm bond, and may be so thin that it permits close contact of the juxtaposed leather parts as shown in the drawing, so that no filler is necessary.

The welt 11 is next roughed or, if desired, this operation may be performed prior to its assembly with the upper. If the welt is roughed after the upper has been lasted, the fastening strip 12 may also be roughed at the same time to provide a 30 wide roughed attaching surface to which an outsole may be cemented. Cement is next applied to the welt 11 and the under surface of the fastening strip 12, and an outsole 16 having its marginal portions similarly roughed and coated with 35 cement is placed against the bottom of the welted upper and affixed thereto under pressure in a suitable sole affixing press. Preferably pyroxylin cement is used for this operation as well as for the lasting operation, although it is contemplated 40 that other suitable adhesives may be used in either case.

The assembly of such a shoe is much easier than that of most welted shoes wherein the upper and welt are lasted to a ribbed insole. Further, 45 the step of sewing both the welt and fastening strip along the outside face of the upper is quite simple and facilitates handling of the materials, and the doubling back of the strip pulls the welt and upper neatly into position against the side of the insole, as is indicated in Fig. 3, and at the same time provides a strong sewed joint at 13 which is so arranged that the strip can not readily pull out from its attaching threads.

Instead of a strip, a number of fabric fasten- 55

ing tabs (not shown) may be used, each of which can be sewed to the outer face of the welt and doubled back over the insole.

Another form of shoe embodying this general construction is shown in Figs. 5 to 8. Here, a fabric attaching material of canvas, duck or the like, is provided in the form of an insole ply 112 which is substantially co-extensive with the insole to be employed in the completed shoe. This 10 ply is longitudinally slit at 17 from its heel nearly to its toe, and is provided with a plurality of lateral slits extending from such longitudinal slit toward the edge of the ply. The ply is also provided with marginal locating notches 19 15 which are adapted to be registered with similar notches (not shown) in the edge of an upper to which the described insole ply is adapted to be attached. This upper 110, like that described above, is trimmed at its lasting allowance edge 20 so as to approach but not materially overlap the insole to which it is lasted. A welt 111 is superposed along the outer face of the upper and the insole ply 112 is positioned along the inner side thereof, this operation being facilitated by the 25 slits 17 and 18. These parts are sewed together by a line of stitching 113 located closely adjacent the edge of the upper.

An insole 114, which may be slightly thinner than a conventional insole, is located on the bottom of a last 115 and the upper with its associated welt and insole ply is pulled thereover, the 30 ply affording a gripping means for the pulling over machine. Cement is applied between the insole and the attaching fabric 112, and the latter is affixed to the insole with its various slit sections reassembled in substantially the position indicated in Fig. 5 to provide a composite insole including the parts 114 and 112.

A suitable filler material 119 is packed in the 40 bottom of the forepart of the thus formed lasted upper interiorly of the inseam, and an outsole 116 is attached to the welt 111, either by stitching or cementing.

This form of shoe also provides substantial 45 economies, and is capable of rapid and easy manufacture.

It will be seen that a method of manufacturing welted shoes has been provided which is well suited to fulfill its intended functions.

Since certain changes in carrying out the above process, and certain modifications in the article which embody the invention may be made without departing from its scope, it is intended that all matter contained in the above description or shown in the accompanying drawing 5 shall be interpreted as illustrative and not in a limiting sense.

It is also to be understood that the following claims are intended to cover all of the generic 10 and specific features of the invention herein described, and all statements of the scope of the invention which, as a matter of language, might be said to fall therebetween.

Having described my invention, what I claim 15 as new and desire to secure by Letters Patent, is:

1. In a method of making a shoe, the steps comprising locating a thin insole on a last, providing an assembled upper of a size to approach but not to overlap said insole when pulled over 20 said last, superposing a welt along the outer face of the margin of said upper, providing a fabric insole ply corresponding in shape with said insole, longitudinally slitting said ply from the heel nearly to the toe, slitting said ply laterally from 25 said first slit toward but not to its edges in a plurality of places, stitching the edges of said ply to said upper and welt closely adjacent the edge of the upper, pulling said upper and ply over the last, cementing said ply, and sticking it to 30 said insole with its slit portions closely reassembled.

2. In a method of making a shoe, the steps comprising locating an insole on a last, providing an assembled upper of a size to approach but not 35 to overlap said insole, superposing a welt along the outer face of the margin of said upper, providing a fabric insole ply corresponding in shape with said insole, slitting said ply so as to enable it to be pulled over said last when attached to 40 said upper, stitching the edges of said ply to said upper and welt closely adjacent the edge of the upper, pulling said upper and ply over the last, cementing said ply and sticking it to the insole with its slit portions closely reassembled but 45 not overlapping, and attaching an outsole to said welt.

HENRY B. GORMAN.
